UNITED STATES PATENT OFFICE

2,073,732

WATER COOLING ATTACHMENT

Alvin L. Cosner, Akron, Ohio

Application January 20, 1936, Serial No. 59,970

1 Claim. (Cl. 62—43)

This invention appertains to new and useful improvements in the general art of refrigeration and more particularly to a water or liquid cooling attachment for refrigerators.

5 The principal object of the present invention is to provide means for installation in mechanical refrigerators, ice boxes and other forms of refrigerators whereby water and other liquid can be cooled thoroughly without requiring but a 10 very small space in the refrigerator.

Another important object of the invention is to provide a liquid cooling feature for refrigerators which will not depart from the conventional appearance of the refrigerator.

15 These and other very important objects and advantages of the invention will become apparent to the reader of the following specification.

In the drawings:

Figure 1 represents a fragmentary front elevational view of a refrigerator showing the dispensing faucet.

Figure 2 is a vertical sectional view taken substantially on the line 2—2 of Figure 1.

Figure 3 is a fragmentary vertical sectional view taken substantially on line 3—3 of Figure 2.

Figure 4 represents a fragmentary detailed sectional view taken substantially on line 4—4 of Figure 3.

Referring to the drawings wherein like numerals designate like parts, it can be seen in Figure 2, that numeral 5 generally refers to a conventional refrigerator (preferably of the electric or mechanical type) which includes the front wall 6, top wall 7 and side walls 8 as well as the bottom wall 9 and back wall 10. Numeral 11 represents the refrigerating compartment and against the inner side of one side wall 8 is disposed the flat coiled pipe 12 defining the water cooling coils generally referred to by numeral 13. A suitable frame 14 is secured to the inner side of the wall 8 and straps 15 are secured to this frame and disposed across the convolutions of the coil 13 so as to retain the same firmly in place. Numeral 15' represents the inlet pipe which extends 45 through the side wall 8 to connect to the coil 13

at one end and while numeral 16 represents the outlet pipe which extends downwardly and as at 17 through the back wall of the alcove 18. To the outer end of this pipe 16 the faucet 19 is secured in the usual manner so that it overlies the 5 floor 20 of the alcove 18 in which is located a small depression 21 from which the drain pipe 22 extends to pass downwardly through the bottom 9 and out through the rear wall 10 to any suitable take-off point. A glass or other receptacle 10 23 can be placed on the floor 20 of the alcove 18 in a position underlying the faucet 19.

The usual water supply line 24 is connected to the inlet pipe 15' by way of the valve 25 and if desired beer or other liquid can be run through 15 an adjacent pipe 26 by way of the valve 27 to the intake pipe 15' when the valve 25 is closed.

A guard plate (see Figure 3) denoted by numeral 28 is placed against the coil 13 and suitably secured to the straps 15 and frame 14. Thus the 20 coil is protected from damage.

As can be seen in Figure 4, the guard plate 28 is secured to the straps 15, and this may be by spot-welding or any other conventional method or means. The guard plate bears against the flat 25 coil 12, so that any force or pressure exerted by the ice shifting in the ice compartment will be taken up by the plate, thus preventing damage to the coil.

While the foregoing specification sets forth the 30 invention in specific terms, it is to be understood that numerous changes in the shape, size and materials may be resorted to without departing from the spirit or scope of the invention as claimed hereinafter.

Having thus described the invention, what is 35 claimed as new is:

In a refrigerator, a flat coiled water tube disposed against the inner side of one side wall thereof, a supporting frame for the coil, and a 40 vertically disposed guard plate secured to the said frame between which and the adjacent wall of the refrigerator the said coil is located.

ALVIN L. COSNER. 45
